UNITED STATES PATENT OFFICE.

VICTOR WILLOUGHBY, OF JEFFERSONVILLE, INDIANA, ASSIGNOR TO WILLIAM H. MINER, OF CHAZY, NEW YORK.

YOKE FOR DRAFT-RIGGINGS.

1,178,117.

Specification of Letters Patent.

Patented Apr. 4, 1916.

Application filed March 18, 1915. Serial No. 15,220.

To all whom it may concern:

Be it known that I, VICTOR WILLOUGHBY, a citizen of the United States, residing at Jeffersonville, in the county of Clark and State of Indiana, have invented a certain new and useful Improvement in Yokes for Draft-Riggings, of which the following is a full, clear, concise, and exact description, reference being had to the accompanying drawings, forming a part of this specification.

This invention relates to improvements in yokes for draft riggings.

An object of the invention is to provide a yoke for draft riggings which consists of two members adapted to be attached to a draw-bar and to be interlocked and prevented from lateral separation by means formed integrally on the two parts.

The invention furthermore consists in the improvements in the parts and devices and in the novel combinations of the parts and devices, as herein shown, described or claimed.

In the drawing forming a part of this specification, Figure 1 is a side elevation of a yoke embodying my improvements and showing the coupler in dotted lines. Fig. 2 is a top plan view of the structure illustrated in Fig. 1. Fig. 3 is a front end elevation of the improved yoke. Fig. 4 is a vertical transverse sectional view taken substantially on the line 4—4 of Fig. 1 and Fig. 5 is a view similar to Fig. 4 illustrating another form of my improvements.

In said drawing, the yoke which is designated generally by the reference A is shown as comprising two, preferably like members B, each of said members B having an upper arm 10, lower arm 11, rear connecting member 12 and front side wall 13, all of said members 10, 11, 12 and 13 being arranged so as to form a pocket for the reception of the usual followers and gear of a draft rigging. Each side plate 13, as shown, is slotted as at 14 for the reception of a coupler key in case the same should be employed. On their inner faces, the arms 10 and 11, at their forward ends, are provided with inwardly turned shoulders 15—15 arranged to engage the usual upper and lower shoulders 16—16 formed on a draw-bar 17. For purposes of strength, the upper and lower arms 10 and 11 are each provided with longitudinally extending ribs 18 on their outer edges and ad-

ditional strengthening ribs 19 may be provided at the front end (see Figs. 2 and 3). In order to prevent the lateral separation of the two loop yoke members B when the latter are in operative position and at the same time to permit easy assembling thereof, I provide each member B, near the center longitudinally thereof, with an overhanging lip 20, which lips 20 are adapted to engage and coöperate with correspondingly formed ribs 21—21, the lips 20 and ribs 21 as shown in the structure illustrated in Figs. 1 to 4 inclusive being confined entirely within vertical planes coincident with the sides of the yoke members B. As shown in Fig. 5, the lips 120 are extended so as to overlap the corresponding outer ribs 118 of the adjacent yoke members.

As will be apparent, the yoke is assembled with the draw-bar by first placing one member B in operative position thereon and then the second member B is applied by sliding it longitudinally relatively to the draw-bar and the other member B until the second member B has its inturned shoulders 15 in engagement with the draw-bar shoulders 16. During this operation, the lips and coöoperative ribs will slide into engagement with each other and when so engaged, the yoke members B B cannot be separated laterally. Also, when the followers and gear are applied within the openings of the yoke, accidental relative longitudinal movement of the yoke members B will be prevented, although limited relative longitudinal movement is permitted between the yoke members in the event that an eccentric load is applied to the gear in the movements of the draw-bar.

As will be apparent, by locating the locking means for the yoke members near the center thereof, longitudinally, I avoid danger of interference with the usual stops on cheek castings employed in the draft rigging. Furthermore, the effect resulting from any tendency to spread the two yoke members apart, as for instance when the draw-bar is swung laterally from the center line of the gear, is minimized.

For cheapness in manufacture the two yoke members B, B are preferably made of like form so that they may be cast from the same pattern. I have shown my improvements in connection with a yoke having a single pocket only but, as will be apparent to those skilled in the art, the improvements

are equally applicable to yokes of other types such as the tandem and hence I do not wish to be limited to the exact structure shown in the drawings but contemplate all changes and modifications as come within the scope of the claim appended hereto.

I claim:—

A yoke of the character described comprising two members arranged for engage-

ment with a coupler said members having integral, coöperating, slidably engaging means located near the longitudinal center thereof to prevent lateral separation when the parts are in assembled position.

VICTOR WILLOUGHBY.
